UNITED STATES PATENT OFFICE.

CHARLES T. ADAIR, OF TECUMCARI, NEW MEXICO.

AIR-COOLED REFRIGERATOR.

1,305,862.

Specification of Letters Patent. Patented June 3, 1919.

Application filed September 20, 1918. Serial No. 254,980.

To all whom it may concern:

Be it known that I, CHARLES T. ADAIR, a citizen of the United States, residing at Tecumcari, in the county of Quay and State 5 of New Mexico, have invented certain new and useful Improvements in Air-Cooled Refrigerators, of which the following is a specification.

This invention relates to cooling apparatus and refrigerators, and in particular it 10 appertains to an air cooling refrigerator of the evaporator type.

A purpose of the invention is to design and render practical an adequate system of 15 evaporating water under a slight air pressure draft introduced into the refrigerator casing, and to provide an effective and capable refrigerator for domestic and other uses which will not require ice for lowering 20 the temperature in the refrigerator.

Another purpose of the present invention is to provide a system of water absorption 25 wicks in combination with a mechanically driven fan for setting up a certain degree of evaporation which will effectively absorb the heat found within the refrigerator, and create a cool zone within the portion of the refrigerator casing set aside to contain the cooling system.

30 A still further purpose of the invention is to combine with the aforesaid purposes a removable form of skeleton like frame which carries the essential absorption wicks and other parts comprising the refrigerator.

35 This frame is arranged as a unit and may be easily removed without taking it apart. In this manner it can be constructed separately and may be inserted in any form of casing adapted to receive it. In this manner 40 it will be practical to convert some forms of ice refrigerators to my form of air cooled refrigerator.

With the above and other purposes in view the invention relates to a certain combination and arrangement of parts, an example of which is described in the following specification, pointed out in the appended claims, and illustrated in the accompanying drawings, wherein:

50 Figure 1 illustrates a vertical sectional view of my form of air cooled refrigerator.

Fig. 2 illustrates a vertical sectional view taken on a plane transversely to the plane section of Fig. 1.

55 Fig. 3 shows the refrigerator in another sectional view, the section being taken hori-

zontally through the lower portion of the refrigerator containing the air cooling and evaporating means.

Referring now more in particular to the 60 drawings, wherein the same parts throughout are designated by the same reference characters, the numerals 1 and 2 point out the front and rear wall respectively. A door 3 is provided for entrance to the casing. A 65 top door 4 is fitted and adapted to be used in removing and replacing the insert unit carrying the cooling system. Side walls 5 are indicated, and the casing in its entirety may be constructed along the scientific 70 approved lines of refrigerator construction, such as insulated walls, or double walls, or other forms which will insulate the interior from the effect of heat from the outside. The refrigerator casing may be a usual type 75 ice refrigerator with the interior removed and made adaptable to receive the air cooling equipment comprising my invention. In this way any home which finds ice inconvenient and expensive may convert their 80 refrigerator into an air cooled home utility.

Taking up the description of the cooling apparatus which is the subject of this invention, there is placed in the lower portion or disposed on the floor of the casing the water 85 containing vessel 6. A set of four vertical supports 7 are provided and braced and held in rigid relation with each other by the horizontal members 8, there being arranged these parts 8 at the top and bottom of the 90 supports.

This structure is set in the containing vessel 6, and forms a skeleton frame for maintaining the system of wicking and water absorption means. A number of shelves 9 are 95 fitted into the frame and form a part of the insert unit. These shelves will be preferably made of perforated material or stiff wire fabric properly reinforced so as to strengthen it sufficiently to maintain the 100 load which it will support. In this instance I have shown the shelves to be made of wire fabric.

A fabric wick 10 is wrapped about the skeleton frame and extends from top to bottom thereof, and into the water containing vessel. This wick is used as the main absorption element to create a cool zone around the casing and completely incloses the skeleton frame insert with the exception of the 105 front where it is left open so that entrance to the shelves and interior may be gained

through the door 3. This main cooling wick will, through capillary attraction, conduct the moisture from the water pan or vessel upwardly to the top of the refrigerator. 5 The top and bottom of the insert is not covered by the wick. The top shelf is therefore accessible through the top door. The wick may be secured to the frame by spring clips 11, or other means. This will permit 10 the wick to be removed for washing and sanitation.

A water cooler or containing vessel for drinking water may, if desired, be installed in the frame-insert at any convenient place 15 and a faucet or valve to draw off the water as needed may be connected therewith and conveniently placed outside so that cool water may always be on tap.

A refrigerating wick 12 is arranged in 20 folds in the lower portion of the casing. This wick is centrally supported underneath the bottom shelf by a pair of rod supports 13. The wick is drawn and maintained in a taut condition by being passed over another rod 14 which holds it in the water pan and immersed in the water contained therein. The wick is further led over another pair of supports 15 and then downwardly where the ends are attached to the 25 frame by clips or other removable means. It is seen that the wick has a number of contacts with the water pan and will rapidly take up the moisture maintaining itself in a continual maximum saturated condition.

30 A fan 16 is provided and housed in a casing fixed upon one side of the refrigerator casing. This will be a spring or electrically driven fan and will be provided with a starting button accessibly located. 40 The fan housing is introduced through an opening in the casing and positioned axially in line with the lower shelf and horizontal portions of the refrigeration wick. This divides the cooling draft and passes same 45 above and beneath the wick.

The air pressure draft directed over the refrigerating wick and beneath thereof sets up a continual evaporation of the water contained in the said wicks and thus lowers the 50 temperature within the refrigerator. Considerable area of fabric wicking is presented to the draft by the arrangement of the several folds which dip into the water pan. The air pressure exerted against the dampened 55 fabric wicks penetrates said wicks and passes through the weave of same and upwardly through the refrigerator. The outer

lining of fabric wicking comes within the influence of the upwardly turned air draft and gives up a certain quantity of moisture 60 and thus creates a cool zone adjacent the casing.

This form of refrigerator is most economical in maintenance and will be found practical and useful to a high degree on the farm 65 and in general domestic use.

The invention is presented to include all such modifications and changes in design or form as may be found to come within the following claims.

Claims:

1. In an air cooled refrigerator, the combination with a refrigerator casing, of a skeleton frame insert comprising support legs spaced apart by horizontal struts and shelves built into the frame the whole of said frame non-attached to the casing and removable therefrom, a water vessel arranged to hold the frame, a sheet of fabric wicking wrapped about the frame and dipped into the vessel, and air pressure means supplied to evaporate the water from the wick to lower the temperature within the casing.

2. In an air cooled refrigerator of the evaporator type, the combination with a casing, of a skeleton frame insert comprising support members fitted with shelves and having the lower and upper ends formed open, and said frame removable from the casing, a refrigerating wick arranged in folds in the lower portion of the insert frame, a water vessel disposed in the lower portion of the casing and adapted to receive the frame, and means for creating an air pressure draft within and against the system of wicking.

3. An air cooled refrigerator, comprising a casing, a skeleton frame insert removable from said casing, wicking extending the length of the frame insert, a water pan in the bottom of the casing and receiving the lower edge of the wicking, a plurality of gauze shelves provided, a single wick arranged beneath the lowermost shelf with outer panels of wicking disposed at an angle and with inner panels disposed at an angle, and a fan arranged to project an air stream on the panels, and the lower edge of each panel dipping into the water pan.

In testimony whereof I hereunto affix my signature.

CHAS. T. ADAIR.
